HYDRAULIC CIRCUIT FOR PRESS BRAKES

Paul E. Flowers, Mount Gilead, Ohio, assignor to
The Hydraulic Development Corp., Inc., Wil-
mington, Del., a corporation of Delaware

Application May 16, 1940, Serial No. 335,596

6 Claims. (Cl. 100—71)

The present invention relates to presses, and in particular to presses having a plurality of spaced pressing plungers connected with one and the same platen. Such machines, which are particularly useful for forming long extended parts, such as airplane wings, and which include the so-called press brakes, shear brakes, and bending brakes, have heretofore been operated mechanically to assure a uniform movement of the ends of the platen as far as possible. Nevertheless, with the said known presses, an asynchronous movement of the spaced pressing plungers has often been encountered with the result that one end of the platen is moving ahead of the opposite end, thereby causing a cocking of the platen and great wear of the plungers, in addition to spoiling the workpiece.

Moreover, the said mechanical presses are relatively complicated in construction and expensive in manufacture.

Accordingly, it is an object of the present invention to provide a machine which would overcome the above identified drawbacks.

It is a further object of the invention to provide a multi-plunger press of the above character in which synchronous movement of the spaced plungers connected with the ends of a pressing platen, bending beam, or shear is assured by hydraulic means.

Another object is to provide a machine, as set forth in the preceding paragraph, in which the total force necessary for performing a working operation on a given workpiece will remain the same, irrespective of the location of the workpiece with respect to the ends of the press platen, bending beam, or shear.

A still further object of the invention consists in providing a press with spaced multi-cylinder piston assemblies operatively connected with one and the same platen, beam or shear, in which the pressing, bending or shearing forces exerted by each cylinder piston assembly automatically adjust themselves in correspondence to the location of the workpiece with respect to the ends of the platen or the cylinder piston assemblies operatively connected therewith.

These and other objects and advantages of the invention will appear more clearly from the following specification in connection with the accompanying drawings, in which:

Figure 1 is a diagrammatic illustration of a press brake according to the present invention, while

Figure 2 shows a graph illustrating the automatic distribution of the individual forces act- 55

ing on the individual plungers in correspondence to the location of the workpiece with respect to the ends of the platen.

The press brake, illustrated in the drawings, 5 comprises a plurality of cylinders 1, 2, each having two chambers 3, 4, 5, 6, respectively separated from each other by a partition 7, 8. Reciprocably mounted in the cylinder chamber 3 is a double-acting piston 9 having connected thereto a plunger 10 passing through a closely fitting bore 11 into the cylinder chamber 4. Any convenient means may be provided for preventing leakage from the chamber 3 below the piston 9 into the chamber 4. Reciprocably mounted in the chamber 15 4 is a double-acting piston 12 having connected therewith a ram 13, which in its turn is connected with one end of the platen 14.

The piston 12 is connected with the plunger 10 in any convenient manner, but so that the effective area on the upper and lower surfaces of the piston 12 is the same. It will be noted that in contra-distinction thereto, the piston 9 has a larger upper surface or advance area and a smaller lower surface or retraction area.

Similarly to the cylinder 1, the cylinder 2 comprises two pistons 15 and 16 arranged in tandem and connected with each other by means of the plunger 17, while the piston 16 is connected by a ram 18 of the same diameter as the plunger 17 with the other end of the platen 14. Each of the pistons 12 and 16 is preferably provided with a collar 19, 20, respectively, for abutment with the lower surface of the partitions 7, 8, respectively.

Supported by the upper ends of the cylinders 35 1 and 2 is a fluid reservoir or surge tank 21 comprising surge valves 22 and 23 extending respectively into the cylinders 1 and 2. The surge valve 22 is connected with a main cylinder relief and pump by-pass valve 24, while the surge valve 23 40 is hydraulically connected with a similar relief and pump by-pass valve 25. The purpose of the said surge valves and relief and pump by-pass valves, which in themselves do not form a part of the present invention, is to release the pressure in the main cylinder chambers 3 and 5 above the pistons 9 and 15 at the beginning of the retraction stroke, while the surge valves enable fluid to flow from the fluid reservoir or surge tank into the upper portion of the main cylinder chambers 3 and 5 at the first portion of the downward stroke of pistons 9 and 15.

For a more detailed description of the surge valves referred to, reference may be had to United States Patent 2,193,248 to Walter Ernst.

The main cylinder relief and pump by-pass

valves 24 and 25 are more fully explained in United States patent application #286,063 to Ernst, filed July 24, 1939.

Connected with the upper portion of the cylinder chamber 3 is a conduit 26 leading to conduit 27, which communicates with one side of a variable delivery pump 28, the other side of the variable delivery pump 28 being connected by means of conduits 29 and 30 with the lower part of the cylinder chamber 3. Branching off from the conduit 30 is a conduit 31 having connections to the surge tank 21 and the main cylinder relief and pump by-pass valve 24, while another branched conduit 32 is adapted to communicate with the surge tank 21 by means of the check valve 33.

Similarly, the conduits 27 and 29 are connected with the upper and lower portion of the cylinder chamber 5.

The upper portion of the cylinder chamber 4 communicates with a conduit 34 containing a check valve 35 and leading to the upper portion of the cylinder chamber 3. Similarly, the upper portion of the cylinder chamber 5 may communicate with the upper portion of the cylinder chamber 6 by means of the conduit 36 and the check valve 37 arranged in the said conduit 36.

The connections 34, 35 between the cylinder chambers 3 and 4, and the connections 36, 37, serve to insure that the upper portions of the chambers 4 and 6 above the pistons 12 and 16, are always completely filled with fluid, and that the pressure is the same as in the main pressure cylinder chambers 3 and 5. This also serves to correct any tendency for one side to get out of step with the other through leakage past the pistons.

The upper portion of the cylinder chamber 4, furthermore communicates with a conduit 38 communicating by means of a conduit 39 with the lower portion of the cylinder chamber 6, whereas the upper portion of the cylinder chamber 6 communicates by means of conduits 40 and 41 with the lower portion of the cylinder chamber 4.

Between the conduits 38 and 40 are arranged two oppositely opening check valves 42 and 43 adapted to establish communication between the conduits 38 and 40 on one hand, and a tonnage control valve 44 arranged in a conduit 45 leading to the surge tank 21. The tonnage control valve 44 is adjusted so as to actuate an electric contact at the attainment of a predetermined pressure, thereby causing a reversing movement of the variable delivery pump 28 and initiating the retraction stroke of the pistons 9 and 15.

For a more detailed description of the tonnage control valve 44, reference may be had to United States patent application #214,772 to Ernst, filed June 20, 1938.

Although the operating circuit is shown as a closed circuit, it might equally as well be an open circuit with a pump delivering in one direction only, and with the control of the upward and downward movement of the pistons effected by means of an operating valve.

Operation

Assuming that the position of the press, as shown in Figure 1, corresponds to the end of the retraction stroke and that it is now desired to perform another working stroke, the variable delivery pump 28 is started in any convenient manner, for instance, by energizing an electric motor connected with the pump 28. Fluid pres-

sure will then be delivered by the pump 28 through the conduits 27 and 26 into the upper portions of the cylinder chambers 3 and 5, while the lower portions of the cylinder chambers 3 and 5 are connected through conduits 30 and 29 with the suction side of the variable delivery pump 28. Supposing that the pistons 9 and 15 move downwardly by gravity, fluid pressure delivered by the pump 28 through the conduits 27 and 26 is supplemented by fluid pressure from the surge tank 21 through the surge valves 22 and 23.

Due to the fluid pressure in the chambers 3 and 5, the check valves 35 and 37 open, thereby allowing pressure fluid to flow from the chambers 3 and 5 respectively, into the upper portions of the chambers 4 and 6. While the pistons 9 and 15 move downwardly, the pistons 12 and 16 connected with the plungers 10 and 17 respectively, likewise move downwardly. During this operation, fluid expelled from the chamber 4 below the piston 12 escapes through the conduits 41 and 40 into the upper portion of the cylinder chamber 6 above the piston 16, whereas fluid expelled from the lower portion of the cylinder chamber 6 below the piston 16 escapes through conduits 39 and 38 into the upper chamber 4 above the piston 12. In this way, the increasing spaces above the pistons 12 and 16 are continuously filled with fluid. As soon as the pistons 9 and 15 have moved downwardly to such an extent that the platen 14 engages the work-piece, pressure builds up in the chambers 3 and 5 above the pistons 9 and 15, and will cause closure of the surge valves 22 and 23.

The conduit means 34 and 35 convey the pressure prevailing in the upper portion of the chamber 3 above the piston 9 into the upper portion of the chamber 4 above the piston 12. Similarly, the conduit means 36 and 37 convey the pressure prevailing in the upper portion of the cylinder chamber 5 above the piston 15 to the upper portion of the cylinder chamber 6 above the piston 16. These pressures will also prevail in the conduits 38 and 40 leading to the tonnage control valve 44, by means of the check valves 42 and 43 respectively.

Assuming now that the workpiece 46 has been placed, as shown in the drawings, that is, more adjacent the ram 18 than adjacent the ram 13, it is obvious that when the workpiece is engaged by the platen 14 there will be great resistance at one end of the platen, namely, at that end which is adjacent the plunger 18, while no or little resistance will prevail at the other end of the platen 14 adjacent the ram 13. Consequently, the platen end adjacent the ram 13 will tend to advance more rapidly than the platen end adjacent the ram 18. This is, however, prevented by the fact that the platen end adjacent the ram 13 can advance only when fluid below the piston 12 is adapted to escape into the upper portion of the cylinder chamber 6 above the piston 16. Consequently, the piston 12 and the platen end adjacent thereto cannot advance more rapidly than the piston 16 and the platen end adjacent the piston 16. In this way, synchronous movement of both platen ends is assured.

As soon as the working stroke has been finished, the delivery direction of the pump 28 is reversed in any convenient manner, so that now pressure fluid is delivered by the pump 28 through the conduits 29 and 30 below the pistons 9 and 15, while excessive pressure fluid above the pistons 9 and 15 may escape through the now open surge valves 22 and 23 into the fluid tank.

During the upward stroke of the pistons 9 and 15 and thereby, also, during the upward stroke of the pistons 12 and 16, fluid expelled by the piston 12 from the chamber 4 above the piston 12 is conveyed through the conduits 38 and 39 into the lower portion of the cylinder chamber 6 below the piston 16. In a similar manner, fluid expelled from the chamber 6 above the piston 16 passes through conduits 40 and 41 into the chamber 4 below the piston 12. When the pistons 9 and 15 have finished their retraction stroke, the press comes to a standstill, by any convenient means, or, if desired, may start a new working operation.

In connection with the operation of the press, according to the present invention, attention may be directed to the feature that the total pressing force necessary for carrying out a working operation on a given workpiece remains the same irrespective of the location of the workpiece with regard to the ends of the press platen 14. To more clearly elucidate this feature, three characteristic positions of the workpiece 46 with respect to the ends of the press platen 14 may be considered.

(a) Assume that the length of the platen is 100 inches and that the total force F for carrying out the pressing operation is 80 tons. Assume, furthermore, that the workpiece 46 is pressed so that the distance of its right end from the right platen end is the same as the distance between the left end of the workpiece 46 and the left platen end. Provided that the material is the same throughout the workpiece, it will be obvious that on each of the pistons 9 and 15 a pressing force of 40 tons will be exerted. This situation is illustrated in Figure 2 and marked by the point A on the line L; it will be noticed that the distance between the point A and the line F-F indicating the force f_1 acting upon the piston 9 equals the distance between the point A and the abscissa indicating the force f_2 acting upon the piston 15.

(b) Suppose now that it would be possible to press the workpiece so that its center is just below the right end of the platen 14, that is, 100 inches away from the left platen end. As soon as the right platen end engages the workpiece the piston 15 will, at least for a fraction of a second, be stopped and in this instance the piston 9 will likewise be stopped, since it can move only when pressure fluid, as previously explained, may escape from below the piston 12 into the upper portion of the cylinder chamber 6 above the piston 16. However, a halt of the piston 9 is possible only when the pressure below the piston 12 equals the pressure above the piston 9. This is actually the case in the present instance, and the whole pressing force must be exerted on the piston 15. In other words, while no pressing force is exerted on piston 9, the pressing force on piston 15 equals 80 tons. This position is illustrated by point B at the intersection of the line L with the line F-F.

(c) If the situation be now reversed, that is, when the workpiece is pressed at the left end of the platen 14, the pressing force f_2 upon the piston 15 will become zero, whereas the pressing force on the piston 9 will be 80 tons. This position is indicated by point C located at the intersection of line L of the abscissa.

The automatic adjustment of the pressing forces acting upon the individual pistons in accordance with the location of the workpiece is also of particular importance in connection with shear brakes where the position of the counter-

forces exerted by the workpiece continuously, gradually and progressively changes during the working operation.

It will be understood that I desire to comprehend within my invention such modifications as come within the scope of the claims and the invention.

Having thus fully described my invention, what I claim as new and desire to secure by Letters Patent, is:

1. In combination, a plurality of spaced cylinder piston assemblies connected with a common platen or beam adapted to act on a workpiece, each of said cylinder piston assemblies comprising a plurality of double-acting pistons in tandem arrangement, a pressure fluid source adapted to supply pressure fluid to said cylinder piston assemblies, and conduit means connecting one side of one piston of each cylinder piston assembly with the opposite side of a corresponding piston of another cylinder piston assembly.

2. In combination, a plurality of spaced cylinders, each cylinder comprising two cylinder chambers, a plurality of spaced double-acting pistons, two pistons being reciprocably mounted in each cylinder but in separate cylinder chambers, valve means responsive to a difference in pressure in two adjacent cylinder chambers during the advancing movement of said pistons for hydraulically interconnecting said adjacent chambers, common means mechanically interconnecting all pistons, a fluid source adapted to supply pressure fluid to said cylinders for reciprocating said pistons, and conduit means connecting the advancing side of a piston in one cylinder and the retracting side of a corresponding piston in another cylinder for effecting synchronous movement of all pistons.

3. In combination, a plurality of spaced hydraulic motors, each motor comprising two double-acting pistons arranged in tandem and connected with a common platen or beam, a fluid source adapted to convey fluid pressure selectively to one or the other side of one piston of each hydraulic motor for actuating the same, and conduit means hydraulically interconnecting a pair of the other pistons in such a manner that each side of one piston of said pair is hydraulically connected to the opposite side of the other piston of said pair, whereby to cause synchronous movement of all pistons.

4. In combination, a plurality of spaced cylinder pairs, the cylinders of each cylinder pair being adapted hydraulically to be interconnected, a plurality of spaced pistons reciprocably mounted in each cylinder pair and operatively connected with each other, common means mechanically interconnecting all pistons and adapted to act on a workpiece, means responsive to a difference in pressure on corresponding sides of the pistons of each cylinder pair to establish hydraulic connection between the cylinders of each cylinder pair, a fluid source common to and directly connected with one cylinder of each cylinder pair and adapted to supply pressure fluid thereto for reciprocating a piston in said cylinder, and means hydraulically connecting the other cylinders to assure synchronous movement of all pistons.

5. In combination, a plurality of spaced vertically reciprocable primary pistons, said primary pistons having a larger advancing area and a smaller retracting area, a plurality of spaced vertically reciprocable secondary pistons, said secondary pistons having equal piston areas on each

side thereof and being arranged in tandem with said primary pistons so as to be reciprocable thereby, means mechanically interconnecting all secondary pistons and adapted to act on a work-piece, first conduit means hydraulically connecting the upper side of one secondary piston with the lower side of another secondary piston, and second conduit means separate from said first conduit means for connecting the lower side of said first mentioned secondary piston with the upper side of said last mentioned secondary piston.

6. A hydraulic press comprising a plurality of vertically arranged and spaced primary cylinders, a plurality of spaced secondary cylinders, 15 each primary cylinder being in alignment with

and superposed upon a secondary cylinder, a plurality of double-acting piston pairs with the pistons of each piston pair in tandem arrangement, each piston pair having one piston reciprocably mounted in one primary cylinder and the other piston reciprocably mounted in the adjacent secondary cylinder, a fluid source adapted to supply pressure fluid to said primary cylinders for reciprocating said piston pairs, a platen connected with said piston pairs, and means adapted to allow equalization of the pressure prevailing in the upper portion of one secondary cylinder with the pressure prevailing in the lower portion of another secondary cylinder.

PAUL E. FLOWERS.
